US0D1060668S

(12) **United States Design Patent** (10) **Patent No.:** **US D1,060,668 S**
(45) **Date of Patent:** **** Feb. 4, 2025**

(54) **ELECTRONIC PEG BOARD DEVICE**

(71) Applicant: **Qr8 Health Inc.**, Cleveland, OH (US)

(72) Inventors: **Christopher Pekrul**, Boston, MA (US);
Kenneth Rhodes, Boston, MA (US);
Sean Robertson, Boston, MA (US);
David Schindler, Cleveland, OH (US)

(73) Assignee: **Qr8 Health Inc.**, Cleveland, OH (US)

(**) Term: **15 Years**

(21) Appl. No.: **29/877,782**

(22) Filed: **Jun. 12, 2023**

CLAIM

The ornamental design for an electronic peg board device, as shown and described.

DESCRIPTION

FIG. 1 is a top, front, left perspective view of an electronic peg board device, showing our new design;

FIG. 2 is a top, left perspective view thereof;

FIG. 3 is a top plan view thereof;

FIG. 4 is a bottom plan view thereof;

FIG. 5 is left-side elevation view thereof;

FIG. 6 is right-side elevation view thereof;

FIG. 7 is a front elevation view thereof; and,

FIG. 8 is a back elevation view thereof.

The broken lines of even length shown in the drawings illustrate portions of the device that form no part of the claimed design.
